[57] CLAIM

The ornamental design for a control panel for an electric guitar or the like, as shown and described.

DESCRIPTION

FIG. 1 is a front, top and right side perspective view of a control panel for an electric guitar or the like showing my new design;

FIG. 2 is a left side elevational view; and

FIG. 3 is a rear elevational view.

The bottoms of the nine screws are conventional and are omitted in all of the Figures for convenience of illustration.

FIG 1.

FIG 3.
